W. L. DE REMER.

TIE PLATE.

APPLICATION FILED AUG. 23, 1909.

1,075,312.

Patented Oct. 7, 1913.

UNITED STATES PATENT OFFICE.

WILLIAM L. DE REMER, OF CHICAGO, ILLINOIS.

TIE-PLATE.

Specification of Letters Patent.

Patented Oct. 7, 1913.

1,075,312.

Original application filed June 18, 1908, Serial No. 439,159. Divided and this application filed August 23, 1909. Serial No. 514,083.

To all whom it may concern:

Be it known that I, WILLIAM L. DE REMER, a citizen of the United States, residing at Chicago, in the county of Cook and State of Illinois, have invented certain new and useful Improvements in Tie-Plates, of which the following is a specification.

This invention relates to metal tie-plates and the object thereof is to provide a tie-plate of comparatively simple and economical construction and efficient and durable in use.

Speaking in general terms, my tie-plate consists of a body portion or plate proper having on its upper face near one end a transverse shoulder coöperating with one side of the rail flange, and bosses or reinforcements on such upper face adjacent the spike holes, one side of such bosses being adjacent said shoulder and by preference formed integral with and extending at an angle from the same. Also by preference the bottom face of the plate is provided with a flange or flanges which in the present instance extend longitudinally of the plate, that is, at an angle to said shoulder.

I do not herein claim the novel methods of forming my tie-plates and severing the same from blanks or bar, as the same constitute the subject matter of an original application filed by me on June 18, 1908, Serial No. 439,159, and issued on October 12, 1909, as Patent No. 936,423, and of a second divisional application filed simultaneously here-
35 with on August 23, 1909, Serial No. 514,082, and issued on January 3, 1911, as Patent No. 980,500.

In the drawing Figure 1 is a plan view of a portion of the blank or bar which is separated into proper lengths to form my new tie-plates; Fig. 2 an edge view of the blank of Fig. 1; Fig. 3 a plan view of one of my tie-plates; Fig. 4 a perspective view thereof; Fig. 5 an end view of the plate; Figs. 6, 7 and 8 sections on the lines corresponding to said figures as indicated on Fig. 3; and Fig. 9 a side elevation of one of my tie-plates in position on a tie and illustrating screw spikes and a rail also in position.

50 In practice a series of my tie-plates are formed in a long blank or bar A a portion of which is illustrated in Fig. 1, which is subsequently severed or cut into proper lengths to form the separate tie-plates.

55 This blank is formed on its upper face or

side with a series of transverse shoulders a and with bosses a' which by preference and as herein shown are integral with said shoulders and extend at an angle therefrom as clearly shown in Figs. 1 and 2. Also by 60 preference and as shown the other or under face or side of the blank or bar is provided with longitudinal flanges a^2 which are here shown as extending at an angle to the shoulders and below the bosses. In practice the 65 blank or bar is covered transversely at points intermediate the ends of the bosses a' as indicated by the dotted lines A'. This results in the production of the separate tie-plates such as shown in Fig. 3, it being ob- 70 vious from Fig. 1 that after said severing operation the bosses of the blank form the bosses at the end of one plate and the opposite end of the next adjoining plate. At the proper time (in practice before the 75 shearing or severing of the blank into tie-plate lengths) the spike holes a^3 are punched or otherwise provided in the tie-plates and through the bosses for the purpose of receiving the spikes which according to modern practice are usually screw type as indicated at B in Fig. 9. The upper surfaces of the bosses A' are upwardly and outwardly inclined from the spikeholes to form supports for the heads of the screw spikes. The 85 resulting tie-plate is thus comparatively simple in construction and is efficient in use, the arrangement of transverse shoulder and bosses serving not only to materially strengthen the body of the plate and to securely hold the rail but also to effectually reinforce and support the spikes which are given a particularly broad bearing by the bosses which, moreover, reinforce and strengthen the plate at the spike holes 95 where it is liable to be weakened. Furthermore, said construction of tie-plate serves to effectually resist lateral strains and side thrusts to which the rail is subjected in use.

I claim:

1. A tie-plate for rails comprising a body portion having near one end a transverse shoulder which is substantially vertical to said body portion and which forms a supporting surface for one side of the rail base and having a boss integral with said body portion and at an angle to the plane of the shoulder and extending adjacent to the line of the edge of the rail base, which boss has a 110

- spike hole with walls arranged to support the back and sides of the shank of a spike and is inclined upwardly from the hole toward said end of the plate to form a backing for the head of the spike, said body portion having near its other end a boss provided with a spike hole.
2. A tie-plate for rails comprising a body portion having near one end a transverse shoulder which is substantially vertical to said body portion, and which forms a supporting surface for one side of the base of a rail, and having a boss integral with said body portion and at an angle to the plane 10 of the shoulder, which boss has a spike hole with walls arranged to support the back and sides of the shank of a spike and is inclined upwardly from the hole toward said end of the plate to form a backing for the head 15 of the spike, said body portion having at its other end a boss which is provided with a spike hole and which at its inner end, toward the rail, is inclined to the body portion.
25. 3. A tie-plate for rails comprising a body portion having near one end a transverse shoulder which is substantially vertical to said body portion and which forms a supporting surface for one side of the base of 30 the rail, and also having a pair of bosses provided with spike holes and arranged to support the shank of the spike as to more than half of its circumference and to back the head thereof, said shoulder connecting said 35 bosses, and said body portion having near its other end a second pair of bosses integral with such body portion and having spike holes.
4. A tie-plate for rails comprising a body portion having near one end a transverse shoulder which is substantially vertical to said body portion, and which forms a supporting surface for one side of the base of 40 the rail, and also having a pair of bosses integral with said body portion and with 45

said shoulder and extending at an angle to the plane of the shoulder, said shoulder being located between said bosses, said body portion having near its outer end a second pair of bosses integral with such body-portion and having spike holes, said first-named bosses being inclined on their top faces to correspond with the inclined under faces of the heads of screw spikes and being arranged to surround and thereby brace the 50 spike shanks below such heads, and the last-named bosses being inclined on their inner sides to the body-portion.

5. A tie-plate bar or blank from which a series of tie-plates is formed and which has on one face a series of transverse shoulders and extended bosses arranged adjacent and at an angle to the shoulders whereby when the blank is severed through the bosses separate tie-plates will be formed each with a 60 transverse shoulder at one side, bosses adjacent thereto and corresponding bosses at the other end of the plates; substantially as described.

6. A rolled tie-plate bar having a series 70 of transversely arranged bosses thereon and adapted when cut through such bosses the plate so formed will have spike supporting bosses on the ends of the same.

7. A rolled tie-plate bar having a series of 75 transversely arranged bosses thereon and adapted when cut through such bosses the plate so formed will have spike head supporting bosses on the ends of the same.

8. A rolled tie-plate bar having a series of 80 transversely arranged bosses thereon having inclined upper faces and adapted when cut through such bosses the plate so formed will have spike supporting bosses on the ends 85 of the same for supporting the spike-heads.

WILLIAM L. DE REMER.
